**COMPOSITIONS AND METHOD FOR PRODUCING
SKELETAL MUSCLE RELAXATION**
Heinz M. Wuest, 150 E. 56th St.,
New York, N.Y. 10037
No Drawing. Filed Nov. 12, 1964, Ser. No. 410,790
5 Claims. (Cl. 167—65)

This application is a continuation-in-part of copending application Ser. No. 262,846 filed Mar. 5, 1963 now U.S. Patent No. 3,192,200.

This invention relates to a novel method of producing skeletal muscle relaxation and relates more particularly to a novel method of producing skeletal muscle relaxation by the administration of a compound of the formula:

in which R₁ represents a cycloalkylmethyl group such as cyclopropylmethyl, cyclobutylmethyl or cyclopentylmethyl and R₂ represents hydrogen, lower alkyl, lower alkoxy or halogen such as chlorine or bromine, and the corresponding medicinally acceptable acid addition salts thereof.

The invention also includes within its scope novel pharmaceutical compositions containing the above compounds.

The therapeutic basis for the use of a muscle relaxant is the release of muscle spasms and spasticity resulting from various neuro-muscular and musculo-skeletal disorders which may result from direct trauma to muscle, multiple sclerosis, arthritis, bursitis, sciatica, etc., or may result in low back pain.

There are several available drugs for the relief of these conditions and they can be classified according to their site of activity in the neuro-muscular system. Thus, for example, there is the so-called "true muscle relaxant" such as quinine which acts directly on the muscle to achieve relaxation. There is also the myoneuro junction type of drug such as curare, gallamine and the like which achieves muscle relaxation by blocking the myoneuro transmission of impulses and there is a miscellaneous group of drugs which act by a variety of complex mechanisms on the interneuronal systems such as meprobamate, carisoprodol, metaxalone and the like.

While there are many such drugs, none of them is ideal for true muscle relaxant therapy either because of lack of specificity of action, lack of oral activity or because of undesirable side-effects which accompany their administration. Thus, for example, curare which is one of the more potent muscle relaxants has to be administered parentally in order to achieve its effect. Obviously, such route of administration besides its discomfort and low safety margin is also highly impractical to patients where repeated dosages are required. These drugs are

2

therefore of limited application. On the other hand, meprobamate while orally active actually achieves its muscle relaxant activity by way of its tranquilizing and sedative activity. In other words, the muscle relaxant activity is one which is subsidiary to its tranquilizing activity. Therefore, in order to achieve the desired muscle relaxant effect, for example, the patient is subject to the undesired side-effects of a central depressant such as tranquilization, sedation or hypnosis. These central depressant effects are clearly undesirable if one wishes to produce muscle relaxation, particularly in instances with organic neurological syndromes such as cerebral palsy, Parkinson's disease or others where uncontrolled motor activity is a primary factor. The shortcomings of having to administer the drug by intravenous or intramuscular administration or the undesirable production of concomitant sedation or other central nervous systems depressant effect clearly indicates that there has been a long-felt need for a reliable and orally effective muscle relaxant free of the aforementioned disadvantages.

Accordingly, a primary object of this invention is to provide a novel method for the production of muscle relaxation without other central depressant effects.

Another object of this invention is to provide muscle relaxation by administration of a drug composition which is effective orally.

Other objects and advantages of this invention will become apparent from the following detailed description.

According to this invention clinically desirable and effective muscle relaxation may be produced by the administration of a composition containing as active ingredient a compound corresponding to structure (I) above or its corresponding acid addition salt. Useful acid addition salts include, for example, the hydrochlorides, the nitrates, the phosphates, the sulfates and the like.

The preparation of these compounds (I) is fully described in aforesaid copending application Ser. No. 262,846.

It has been found, for example, that the compound 7-chloro-1-cyclopropylmethyl-1,3-dihydro-5-phenyl-2H-1,4-benzodiazepine-2-one and its acid addition salts produces significant muscle relaxant activity on oral administration to warm-blooded mammals, without any observable central nervous system depressant effects.

Thus, in a laboratory test using warm-blooded mammals such as mice as the experimental animal, for example, effective muscle relaxation has been achieved at an oral dose of 74 mg./kg. whereas the well-known meprobamate required an oral dose of 282 mg./kg. to produce the equivalent effect but this degree of muscle relaxation with meprobamate is also accompanied by an appreciable degree of sedation. On the other hand, in

human beings an oral dose three times a day of 25 mg. is capable of producing a clinically effective degree of muscle relaxation in a variety of neuro-muscular disorders but without observable sedation. This remarkable effect is believed to be due to the specific interneuronal blockage within the spinal cord produced by these compounds rather than by the collateral depression of the central nervous system such as that caused by other known muscle relaxants. In addition, the muscle relaxant activity produced by the compounds of this invention has a rapid yet very smooth onset of very long duration.

The pharmaceutical compositions of the present invention comprise as active ingredient a compound of the structure (I) in combination with a nontoxic pharmaceutical carrier adapted for human or veterinary medication; the selected active ingredient being present in an amount from about 10 to about 100 mg. per dosage unit. These oral dosage forms include, for example, solid compositions such as tablets and pills; dispersible powders or granules; or semisolid and liquid formulations in the form of syrups, solutions, suspensions or dispersions.

The above compositions may also include other known therapeutic agents such as, for example, analgesics, anti-inflammatory agents, cardiovascular agents, sedatives, steroids, tranquilizers, antacids, and the like. These analgesics include, for example, aspirin, namol xenyrate, N-acetyl-p-aminophenol and the like.

The anti-inflammatory agents in these compositions may include, for example, prednisolone, cortisone, N-methyl-yohimbane and the like. Cardiovascular agents includes, for example, quindonium bromide, pentaerythritol tetranoate and the like. Sedatives include, for example, phenobarbital, butylbarbital, and the like. The steroids may include, for example, estrogen, testosterone, and the like. Tranquilizers which may be included are, for example, the phenothiazines such as mepazine, the rauwolfia alkaloids such as reserpine, and the like.

As stated, it has been found that the above compounds produce muscular relaxation without tranquilizing effect. However, tranquilization may also be achieved accompanied by the desired muscle relaxation by administering the active ingredient at higher doses, that is to say, the separation of the muscle relaxant activity from the tranquilizing activity of the compounds of this invention is achieved by suitably modifying the dosage thereby giving the prescriber a choice, which, of course, is a great advantage. Generally, a dosage of 5 to 25 mg. administered several times daily is sufficient to maintain adequate muscle relaxation; a higher dose such as 50 mg. several times daily producing, in addition, a tranquilizing action.

The following examples are included in order further to illustrate the invention:

Example 1

In order to demonstrate the muscle relaxant effect of 7-chloro-1-cyclopropylmethyl-1,3-dihydro-5-phenyl-2H-1,4-benzodiazepine-2-one, graded doses of this drug are administered orally to a series of unanesthetized adult mice divided into groups of ten. The pharmacological test employed consists in placing the treated mice on an inclined screen having a mesh size of 1. Muscle relaxant activity in the mouse is observed as the inability of the treated animals to remain on the screen inclined at 30°. The treated mice are observed at hourly intervals for about six hours. Untreated mice are included in the test as controls. Approximate effective dose 50 (ED₅₀) for muscle relaxant activity is that dose at which 50% of the treated animals are unable to remain on the screen. By this test, the effective oral dose of this compound has been found to be 74 mg./kg. whereas that of meprobamate is found to be 282 mg./kg. In another series of experiments the same compound is also administered to cats at graded doses. The treated animals are observed for muscle relaxant activity by noting the ability of the drug to produce alterations in gait and palpitation of muscle tone. The ED₅₀ of this compound is found to be 5 mg./kg. whereas the ED₅₀ of meprobamate is found to be at 25 mg./kg.

Example 2

The lack of central depressant effect of 7-chloro-1-cyclopropylmethyl-1,3-dihydro-5-phenyl-2H-1,4-benzodiazepine-2-one is noted by its failure to produce hypnosis as demonstrated in the following test procedure.

Adult female albino mice weighing about 18 to 24 grams are given orally a 1% by weight solution of the above compound in polyethylene glycol at graded doses.

As a basis for comparison, other groups of mice are given equivalent doses of chlordiazepoxide, meprobamate and diazepam. The mice are then observed for any hypnotic effects produced. The dose at which 50% of the mice show hypnosis is determined and this dose in keeping with accepted terminology is defined as the ED₅₀. The higher the ED₅₀ the less active is the test compound in producing a noticeable central depressant effect. The results obtained by this test procedure are tabulated as follows:

	ED ₅₀ , mg./kg.
(1) 7-chloro-1-cyclopropylmethyl-1,3-dihydro-5-phenyl-2H-1,4-benzodiazepine-2-one	>1000
(2) Diazepam	104
(3) Meprobamate	300
(4) Chlordiazepoxide	415

Example 3

The following toxicity test demonstrates the safety of 7-chloro-1-cyclopropylmethyl-1,3-dihydro-5-phenyl-2H-1,4-benzodiazepine-2-one. In carrying out this test several groups of adult female albino mice weighing about 18 to 24 grams each are employed. Each group receives orally a 1% by weight solution in polyethylene glycol of the above compound in graduated doses and the mice are then observed for one week. The particular dosage of the material administered at which 50% of the test mice survive, expressed in milligrams, is reported as the average lethal dose is referred to as the ALD₅₀. The higher the ALD₅₀ the lower the toxicity and the greater the safety of the material.

The following tabulation gives the ALD₅₀ of the above compounds as determined by this procedure. The ALD₅₀ values for chlordiazepoxide and diazepam are also included for comparative purposes:

	ALD ₅₀ mg./kg.
(1) 7-chloro-1-cyclopropylmethyl-1,3-dihydro-5-phenyl-2H-1,4-benzodiazepine-2-one	>1000
(2) Chlordiazepoxide	680
(3) Diazepam	750

Example 4

A mixture of 10 parts of 7-chloro-1-cyclopropylmethyl-1,3-dihydro-5-phenyl-2H-1,4-benzodiazepine-2-one and 90 parts of calcium phosphate is granulated by admixture with a sufficient quantity of aqueous 10% starch paste. The granules are passed through a No. 12 screen and are then dried at 50° C. for about 10 hours. The dry granules are then passed through a No. 16 screen, 1 part of magnesium stearate is then added thereto and the mixture is then compressed into tablets on a rotary press at about 100 mg. each, with each tablet containing about 10 mg. of active ingredient.

Example 5

A mixture of 25 parts of 7-chloro-1-cyclopropylmethyl-1,3-dihydro-5-phenyl-2H-1,4-benzodiazepine-2-one and 175 parts of milk sugar are intimately blended together. 200 mg. of this mixture is filled into hard gelatin capsules each of which will contain 25 mg. of the active ingredient.

Example 6

Illustrative of the muscle relaxant activity of 7-chloro-1-cyclopropylmethyl-1,3-dihydro-5-phenyl-2H-1,4-benzodiazepine-2-one in human beings is the following clinical case:

A female patient, 37 years of age, was diagnosed to be suffering from a neuropastic disease. She was treated with the above compound at an oral dose of 10 mg. three times a day. Complete relief was observed after two days' medication.

It is understood that the foregoing detailed description is given merely by way of illustration and that many variations may be made therein without departing from the spirit of my invention.

Having described my invention, what I desire to secure by Letters Patent is:

I claim:

1. A method of producing skeletal muscle relaxation in warm-blooded mammals which comprises administering orally to said mammals an effective amount of a compound of the formula:

in which R_1 is cyclopropylmethyl, cyclobutylmethyl and cyclopentylmethyl and R_2 is a member of the group consisting of hydrogen, halogen, lower alkyl and lower alkoxy and the medicinally acceptable acid addition salts.

2. The method according to claim 1 wherein said compound is administered at about 5 to 25 mg. several times daily.

3. A method of producing skeletal muscle relaxation in warm-blooded mammals which comprises administering orally to said mammals about 5 to 25 mg. of a member of the group consisting of 7-chloro-1-cyclopropylmethyl-1,3-dihydro-5-phenyl-2H-1,4-benzodiazepine-2-one and the medicinally acceptable acid addition salts several times daily.

4. A composition for oral administration consisting

essentially of about 5 to 25 mg. of a compound of the formula:

15 in which R_1 is cyclopropylmethyl, cyclobutylmethyl and cyclopentylmethyl and R_2 is a member of the group consisting of hydrogen, halogen, lower alkyl and lower alkoxy and the medicinally acceptable acid addition salts, in combination with a nontoxic orally ingestible pharmaceutical carrier.

20 5. A composition for administration consisting essentially of about 5 to 25 mg. of 7-chloro-1-cyclopropylmethyl-1,3-dihydro-5-phenyl-2H-1,4-benzodiazepine-2-one and its medicinally acceptable acid addition salts in combination with a nontoxic orally ingestible pharmaceutical carrier.
